UNITED STATES PATENT OFFICE.

WILLIAM A. ELLIOT, OF YONKERS, NEW YORK, ASSIGNOR TO BIGELOW CARPET COMPANY, A CORPORATION OF MASSACHUSETTS.

DESIGN FOR A RUG.

44,780.

Specification for Design.

Patented Oct. 28, 1913.

Application filed September 9, 1913. Serial No. 789,004. Term of patent 3½ years.

To all whom it may concern:

Be it known that I, WILLIAM A. ELLIOT, a citizen of the United States, residing at Yonkers, in the county of Westchester and State of New York, have invented a new, original, and ornamental Design for a Rug of Carpet Sizes, of which the following is a specification, reference being had to the accompanying drawing, forming part thereof.

The drawing illustrates one quarter of a rug, showing my new design, the remaining three quarters become duplicates thereof when the one quarter shown in the drawing is reversed bi-symmetrically from the central axes, both horizontal and vertical.

I claim:

The ornamental design for a rug, as shown.

WILLIAM A. ELLIOT.
